United States Patent

Des. 238,011

Patented Dec. 9, 1975

238,011

CARRYING CASE

Joaquin J. Canton, 707 E. 242nd St.,
Bronx, N.Y. 10470

Filed June 17, 1974, Ser. No. 479,836

Term of patent 14 years

Int. Cl. D3—02

U.S. CL. D87—1 R

FIG. 1.

FIG. 3.

FIG. 2.

FIG. 4.

FIG. 5.

FIG. 1 is a front elevational view of a carrying case showing my new design;

FIG. 2 is a rear elevational view thereof;

FIG. 3 is a side elevational view;

FIG. 4 is an elevational view of the opposite side; and
FIG. 5 is a top plan view.

I claim:

The ornamental design for a carrying case, substantially as shown and described.
